UNITED STATES PATENT OFFICE

ALEXANDER GILLESPIE, OF PITTSFIELD, ILLINOIS

GYRATING BOLTING-CLOTH CLEANER

Application filed March 11, 1929. Serial No. 345,996.

This invention relates to certain new and useful improvements in gyrating bolting cloth cleaners used in flour bolting machines, and similar structures having sifting sieves, and has for one of its objects to provide a device of this character in which provision is made for jarring and preventing the clogging of the bolting fabric, and for eliminating the wear on the frame members which support the fabric caused by the lateral pounding of the cleaning means against the sieve supporting frame.

In the various forms of bolting machines in which finely divided bolting fabric is employed, the meshes of the fabric are liable to become clogged by particles of the material passing therethrough adhering to the fabric, and require to be continuously tapped, rapped or slightly jarred to relieve the fabric from the adhering particles, and to accomplish this result automatically and without injury to the supporting frames of the bolting fabric is the main object of the present invention.

My improved cleaner device may be applied to any of the various forms of machines in which vibratory bolting fabrics are employed, such as flour bolts and the like, but is more particularly applicable to the class in which a gyrating vibratory movement is applied to the frames, and for the purpose of illustration a screen frame of a machine of this character is shown.

In the accompanying drawing in which like reference numerals indicate corresponding parts,

Figure 1 is a plan view of a frame without the bolting fabric, and showing a perforated metallic bottom.

Figure 2 is a transverse section with the bolting fabric in position on the frame.

Figure 3 is an enlarged sectional detail of Fig. 1 including one of the movable cleaning elements; and

Figure 4 is a detail illustrating a modification of said bottom.

The supporting frame is indicated as a whole at 10, and is preferably divided by partitions 11 into a plurality of compartments, four being shown for illustration, but any number of the compartments may be pro-

vided, depending on the size of the machine in which the improved device is installed.

The frame 10 is covered on the upper side with the bolting fabric, indicated at 12, and attached to the lower face of the frame is a perforated element indicated at 13.

The perforated element 13 may be a metal plate as indicated in Figures 1 and 2, with relatively large apertures 14, or a wire screen material may be employed of correspondingly large mesh as indicated at 15 in Figure 4, through which the bolted material freely passes.

Located in each of the compartments defined by the partitions 11 is a cleaner device 16. These cleaner devices may be of any suitable material, but in practice sections of felt or other comparatively soft material preferably having a semi-cylindrical bottom rounded in U-shape in cross section as shown have been found to operate satisfactorily. Each cleaner device is provided with a knob-like projection 17, smaller in diameter than the apertures 14. The cleaner devices are of less size vertically than the space interposed between the fabric 12 and the perforated element 13 or 15. The diameter of the openings 14 of the perforated element 13, or wire screen 15, may be 2 to 2 1/2 times greater than the cleaner projection 17, such that the cleaner projection may have ample clearance within the openings to have free play. The semi-globular knob of projection 17 is of such depth that it projects through the openings 14 and 15 and below the surfaces of the metal sieve bottom. In operation as the cleaner body lies flat on the metal sieve bottom and the cleaner knob projecting through the opening and below the surfaces of the sieve bottom; it will be evident that, as the gyrating motion is transmitted to the cleaner body it will carry the cleaner projection or knob in a swinging kick against the side or sides of the opening and thus cause the cleaner to jump or leap in an oblique angular direction, at the sieve bottom, striking and tapping or jarring the bolting fabric. As the action of cleaner is in an angular direction it is thus continuously changing its position from aperture to aperture over the entire sieve bottom,

95
100

tapping or jarring the bolting fabric throughout its whole surface. Also, the destructive lateral pounding of the inner surfaces of the sieve frame, by the cleaner element, is eliminated and the usefulness of the sieve frame 5 greatly extended.

Some flour bearing stocks are high in 10 moisture content and of very fine granulation and therefore most difficult to bolt. The cleaner projection may be extended or lengthened to project farther through the apertures in the sieve bottom and thus intensify the tapping or jarring of the bolting fabric, and thus the perfect bolting control of 15 variable stock conditions is obtained.

The rounded bottom of said body facilitates inclining the upper surface so that it does not hit flat against the sieve bottom but inclinedly with a swinging kick. Thus a 20 double kick is given as the upper surface of the body hits the fabric, and the fluted surface with sharp contact edges shown in Fig. 3 promotes the sifting of the flour through the fabric. The longitudinal groove shown 25 in the upper surface prevents the clinched ends of the prongs of shank holding the knob 17 to the rounded bottom, from contact with the fabric. Furthermore, the depth of this 30 rounded projection controls the force of its jump when the edge of the aperture strikes it: a lesser projection than that shown makes the body kick with less force against the fabric, while a deeper taper on said projection causes it to hit harder. Thus I can 35 substitute a projection that is suitable to the material being bolted.

Having now described my invention, that which I claim to be new and desire to protect by Letters Patent, is:

1. A bolting sieve cleaner comprising a 40 felted body having a substantially semi-cylindrical bottom, and a tapering metallic knob-like projection secured to the bottom of said body, substantially as described.

2. A bolting sieve cleaner comprising a 45 felted body having a substantially semi-cylindrical bottom and a central longitudinal groove in the top and a rounded metallic projection on said body having vertical prongs extending upward and clinched in 50 said groove, substantially as described.

3. A bolting sieve cleaner comprising a 55 felted body having a substantially semi-cylindrical bottom and fluted top with a longitudinal groove and a rounded metallic projection having a shank extending upward into 60 said groove and secured therein, substantially as described.

4. In a vibratory sieve for sifting 65 machines, the combination with a suitable frame forming an interposed space between a bolting sieve top and an apertured bottom, of a 70 loosely disposed cleaner for said sieve comprising a body of substantially lesser height than 75 said space and having a fluted top and a

semi-globular projection on its bottom, substantially smaller than said apertures adapted to be hit obliquely by the side of the surrounding aperture and impelled inclinedly upward against said sieve, substantially 80 as described.

5. In a sieve for sifting machines, the combination with a bolting sieve top and a bottom having multiple apertures and separated from the top by a space, of a cleaner for said 75 sieve top comprising a body of substantially lesser height than and loosely disposed in said space and having a rounded projection secured to the bottom of said body of a size substantially less than the size of said apertures for allowing initial lateral movement therein, substantially as described.

6. In a sieve for sifting machines, the combination with a bolting sieve top and a bottom having multiple apertures for passage 85 of bolted material, of a cleaner for said sieve top comprising a felted body of substantially lesser height than the interposed space between the sieve top and bottom and having a rounded bottom and loosely disposed in said 90 space, and a rounded metallic projection secured to the rounded bottom of said body and of substantially half the size of the apertures in said bottom adapted to kick said body against the sieve top in its movement from 95 one aperture to another, successively, substantially as described.

7. In a sieve for sifting machines, the combination with a bolting sieve top and a bottom having multiple apertures for the passage 100 of bolted material, of a cleaner for said sieve top comprising a semicylindrical felted body movably disposed on said bottom and of substantially lesser height than the space between said sieve top and bottom and having 105 a metallic rounded projection secured to the rounded bottom of said body and of substantially half the size of said apertures adapted to retard the lateral movement of said body, substantially as described.

In testimony whereof I affix my signature.
ALEXANDER GILLESPIE.
